CLAIM

(21) Appl. No.: **29/152,537**

The ornamental design for a spreader top crown of an outrigger assembly, as shown and described.

(22) Filed: **Dec. 21, 2001**

DESCRIPTION

(51) LOC (7) Cl. **12-06**
(52) U.S. Cl. **D12/317**
(58) Field of Search **D12/317; 114/255,
114/315**

FIG. 1 is a top perspective view illustrating our design for a spreader top crown of an outrigger assembly;
FIG. 2 is a front view thereof;
FIG. 3 is a left side view thereof;
FIG. 4 is a top view thereof;
FIG. 5 is a right side view thereof;
FIG. 6 is a bottom view thereof; and,
FIG. 7 is a rear view thereof.
